James B. Ferguson,
By his Attorney &
Keeney & Keeney

UNITED STATES PATENT OFFICE.

JOSEPH B. FERGUSON, OF NEW YORK, N. Y.

ENGINE.

1,258,665.

Specification of Letters Patent. Patented Mar. 12, 1918.

Application filed October 19, 1916. Serial No. 126,528.

To all whom it may concern:

Be it known that I, JOSEPH B. FERGUSON, a subject of the King of Great Britain, and a resident of the city of New York, county 5 and State of New York, have invented certain new and useful Improvements in Engines, of which the following is a specification.

This invention relates to engines, and particularly to the arrangement of the accessories of an internal combustion engine with relation to each other and to the engine, whereby the inherent and incidental characteristics thereof may coöperate to produce a 10 useful and desirable result.

An object of this invention is to arrange the accessories of an internal combustion engine in such relation to one another, and to the engine that certain characteristics of 20 said accessories and engine which are undesirable shall be neutralized and turned to advantage.

Another object is to arrange the accessories of an internal combustion engine in 25 such relation to one another and to the engine that certain of said accessories shall be incased with the engine and concealed and protected. In the attainment of this object and as a further object, it is my object to 30 keep such accessories from becoming overheated by radiation from the engine or from internal heating, and from becoming moist by taking away such heat or moisture in an air stream, and preferably preheating the 35 fuel mixture, the air being circulated preferably by the suction of the carbureter or by a moving part of the engine.

Other and further objects and advantages 40 will appear from the following description taken in connection with the accompanying drawings forming a part of this specification, and will be pointed out in the hereunto appended claims.

In the drawings, in which like reference 45 characters indicate similar parts,

Figure 1 is a partial elevation of an engine embodying my invention, with parts removed;

Fig. 2 is a partial plan view of the engine shown in Fig. 1; and

Fig. 3 is a transverse section of the engine shown in Fig. 1.

The engine herein illustrated and described is to be considered as one embodiment of my invention, and as being disclosed in detail for the purpose of inter-

preting my invention; and it is to be understood that my invention is not to be limited to the specific details thereof, but is to be defined by the hereunto appended claims. 60

The engine comprises a crank casing made up of the parts 1 and 2 and the cylinders which are covered by casing 3. Upon the portion 2 of the crank case a shelf-like projection 4 is formed. The shelf-like projection 4 and the cylinder casing are shaped to provide a chamber 5 in which there are positioned the generator 6 and the starting motor 7. The electrical devices are partially covered by a housing 10 which has in it a 70 large opening which is normally closed by cover plate 11 held down by nut 12 which engages the threaded end of the stay-bolt 13 which is mounted in the engine frame. The forward part of the chamber which 75 partially surrounds the engine consists of the portion 15 which extends part way across the front of the engine, and the removable portion 16 which extends the remainder of the distance, and which comprises the housing for the magneto 17. The portion 16 is made removable, and it is apparent that by removing the cover plate 11 and the portion 16, all of the electrical devices can be inspected and adjusted. 85

The chamber opens at its rear end into the housing 18 of fly-wheel 19, and the housing 18 has on the other side of the engine an opening which is connected by pipe 20 to the air intake of the carbureter 21. The 90 chamber is provided with openings 22 which are formed in the portion 17, and openings 23 which are formed in the portion 10. When the engine is in operation, the rotation of the fly-wheel, as well as the suction 95 of the carbureter, will cause a circulation of air into the openings 22 and 23 and through the chamber and across the electrical devices therein. The accessories, including the electrical devices of an internal combustion engine, should be incased to as great an extent as possible, and should be firmly attached to the engine for purposes of protection and convenience; and by providing a chamber formed on the engine frame 100 through which air is caused to circulate, I am able to mount the accessories right on the frame of the engine and at the same time withdraw from them by circulation of air, the excess of heat which reaches them 105 by reason of radiation from the engine, and by reason of inherent self-production of

- heat, as in the case of a starting motor or generator; and the circulation of air also prevents the accumulation of moisture in the electrical devices. The circulation of air 5 may be brought about by the movement of the fly-wheel or a fan driven by the engine, or it may be brought about by the suction of the carbureter, and in the latter case the withdrawal of heat from those accessories 10 which it is desired should be kept cool, results in a preheating of the air for the fuel mixture. By reason of the circulation of air in the chamber, there is a slight negative pressure, and I therefore provide communication 15 between this chamber and the crank case by means of a crank case release vent 30, so that a negative pressure exists in the crank chamber and oil is not thrown out through the valve tappet openings. The 20 chamber being provided with sharp corners 31, any dust contained in the air will be caught by reason of the rapid circulation of the air in the chamber, and will not flow into the carbureter.
- 25 It will be apparent from the foregoing that I have arranged the accessories of the internal combustion engine so that the undesirable features are neutralized and turned to advantage.
- 30 Having thus described my invention, what I claim as new and desire to secure by Letters Patent, is:—
1. In an internal combustion engine, a crank casing, a fly-wheel casing, a chamber 35 formed upon said engine for inclosing electrical accessories of said engine and communicating with said fly-wheel casing, and a carbureter for said engine having its air intake communicating with said fly-wheel 40 casing.
  2. In an internal combustion engine, a crank casing, a fly-wheel casing and a chamber formed upon said engine for inclosing electrical accessories of said engine and 45 communicating with said fly-wheel casing, said fly-wheel casing having an outlet opening whereby the action of said fly-wheel will circulate air through said chamber.
  3. In an internal combustion engine, the 50 combination of a crank casing having a plu-

rality of cylinders mounted thereon, a shelf projecting from the longitudinal side of said casing and having a cover providing a closed chamber therewith, electrical accessories within said chamber, air inlets at one end of 55 said chamber and a carbureter connected to the other end of the chamber whereby air for the carbureter is preheated and cools the accessories.

4. In an internal combustion engine, having a crank casing and cylinders mounted thereon, a chamber formed upon said casing of the engine and extending along the side thereof, electrical accessories for said engine and positioned within said chamber, 65 and a carbureter for said engine and having its air intake communicating with said chamber, said chamber being closed except for openings admitting air at points where the air will be drawn across said accessories 70 by said carbureter to cool said accessories.

5. In an internal combustion engine, a chamber formed upon the casing of the engine, electrical accessories for said engine and located in said chamber, and a carbureter for said engine and having its air intake communicating with said chamber, said engine having a crank case communicating with said chamber, substantially as described and for the purpose specified. 75

6. In an internal combustion engine, a chamber formed upon the casing of the engine, electrical accessories for said engine and inclosed in said chamber, and means for withdrawing air from said chamber, said engine having a crank case in communication with said chamber, substantially as and for the purpose described. 80

7. In an internal combustion engine, a chamber formed upon the outside of the 90 casing of the engine for inclosing electrical accessories of the engine and extending partly therearound and comprising a shelf-like portion extending out from the frame of said engine and cover portions resting on 95 said shelf-like portion and forming therewith said chamber.

In testimony whereof, I have signed my name to this specification.

JOSEPH B. FERGUSON.

It is hereby certified that in Letters Patent No. 1,258,665, granted March 12, 1918, upon the application of Joseph B. Ferguson, of New York, N. Y., for an improvement in "Engines," an error appears requiring correction as follows: The name of the inventor as written upon the drawings appears "James B. Ferguson," whereas said name should appear as *Joseph B. Ferguson*; and that the said Letters Patent should be read with this correction therein.

Signed and sealed this 16th day of April, A. D., 1918.

[~~SEAL.~~]

F. W. H. CLAY.

Acting Commissioner of Patents.
